CLAIBORNE W. COOCH, JR., OF LYNCHBURG, VIRGINIA, ASSIGNOR TO UNITED CIGARETTE MACHINE COMPANY, INC., OF LYNCHBURG, VIRGINIA, A CORPORATION OF VIRGINIA

TOBACCO STEMMING MACHINE

Application filed October 28, 1931. Serial No. 571,598.

The present invention relates to improvements in tobacco stemming machines and especially with the means for removing the tobacco strips from the stemming elements, 5 and applying it in particular to the type of stemming machine which has stemming elements mounted on chains at spaced intervals.

It is an object of the invention to provide an auxiliary surface in cooperation with the 10 stripping elements for the purpose of preventing the tobacco from moving out of the range of the cleaning roll or rolls and thereby accomplish or provide for the complete removal of the tobacco from the carding 15 member. It is a further object of the invention to provide various forms for the auxiliary surface.

The invention is illustrated on the accompanying drawings in which like reference 20 numerals indicate corresponding parts throughout and in which:

Figure 1 is a side view with a number of parts in section of the stemming mechanism of a stemming machine showing the yielding 25 surface brushes.

Fig. 2 is a similar view of a modified construction,

Fig. 3 is a view similar to Fig. 1 showing a further modified construction.

Fig. 4 is a view similar to Fig. 1 showing the upper right end of the mechanism of a still further modified construction,

Fig. 5 shows a number of detailed views of a modified supporting surface, and

Fig. 6 shows a number of detailed views of the cleaning rolls.

The operation of the stemming machine as illustrated is as follows:

The tobacco leaves are held by their butt 40 ends 34 between the endless conveyor belts 32 and 33, Figs. 1 to 3. These belts advance the tobacco leaves side ways between the upper and lower pairs of chains 35 and 36 which are carried on the sprocket wheels 45 37, 38, 39 and 40 respectively. Mounted on these chains are bars 4 at regularly spaced intervals each of which are provided with the carding member 5 or other means for stripping the leaves from the stems. It will 50 be seen that as the bars 4 come around their

respective sprocket wheels 37 and 39 in the direction of the arrows they will meet in a cooperative manner and the carding on the corresponding bars will move along the stem of the tobacco to remove the leaf therefrom. When these bars or stripping elements reach sprockets 38 and 40 they separate, a part of the stripped leaf being carried upward by the upper bar and a part is carried downward by the lower bar. A cleaning roll 7, 60 Fig. 1, is provided for brushing the stripped leaf out of the teeth of the carding member 5. A cleaning roll alone, however, does not have the desired effect as the stripped leaf will tend to fall behind or in front of the bars 4 and thereby will be out of reach of the cleaning roll 7. For this reason and according to the invention yielding surfaces are provided to procure a surface for the tobacco leaf. In Fig. 1 the brushes 1 are mounted on a segment 2 secured to the shaft 3 and which provide a yielding surface which is so timed as to follow closely behind the stripper bars 4 which are faced with the carding member 5 to which the tobacco leaves 6 cling after having been stripped from the stems. The brushes 1 form a supporting surface for the leaves 6 and keep the leaves from falling inwardly towards the shaft 3 and away from the cleaning roll 7. The stripped leaves are 70 thus held out in contact with the cleaning roll 7 which is rotating in the direction of the arrow and thereby enables the cleaning roll to pull them out of the teeth of the carding 5. 75

The cleaning roll 7 is shown in Fig. 1 as being composed of wire carding wrapped around a core but it may be composed of thin sheet metal blades as shown in Figs. 2 and 6 or a corrugated roller 10 as shown in Fig. 3 or even a roller having flaps of leather or similar material 23 as shown in Fig. 4.

In Fig. 2 the stripper elements 4 and 5 are both preceded and followed by segmental surfaces 8. These surfaces are integral and secured to the shaft 3. The forward part of segment 8 is provided to prevent the tobacco leaf 6 from falling over the front of the stripping elements 4 and 5 and which will hold the tobacco in the path of the cleaning roll 31. 100

2

5

5 a pair of cooperating stripping elements for stripping the leaf from the stems; a cleaning element for each stripping element adapted to remove the leaf therefrom; and an auxiliary surface cooperating with each stripping element movable against the stripped tobacco leaves to prevent the leaves from moving out of the range of the cleaning element.

10 6. A tobacco stemming machine comprising a pair of cooperating stripping elements for stripping the leaf from the stems; a cleaning element for each stripping element adapted to remove the leaf therefrom; and an auxiliary surface in the form of a brush cooperating with each stripping element movable against the stripped tobacco leaves to prevent the leaves from moving out of the range of the cleaning element.

15 7. A tobacco stemming machine comprising a pair of cooperating stripping elements for stripping the leaf from the stems; a cleaning element for each stripping element adapted to remove the leaf therefrom; and an auxiliary surface in the form of a plurality of brushes cooperating with each stripping element movable against the stripped tobacco leaves to prevent the leaves from moving out of the range of the cleaning element.

20 8. A tobacco stemming machine comprising a pair of cooperating stripping elements for stripping the leaf from the stems; a cleaning element for each stripping element adapted to remove the leaf therefrom; and an auxiliary surface in the form of a brush mounted on the segment, said brush being adapted to follow the stripping element to prevent the leaf from moving out of the range of the cleaning element.

25 9. A tobacco stemming machine comprising a pair of cooperating stripping elements for stripping the leaf from the stem; a cleaning element for each stripping element adapted to remove the leaf therefrom; a rotatably-mounted segment; and an auxiliary surface in the form of a brush mounted on the segment, the forward surface preventing the leaf from falling over the front of the stripping element and the rear surface preventing the leaf from moving beyond the range of the cleaning element.

30 10. A tobacco stemming machine comprising a pair of cooperating stripping elements for stripping the leaf from the stems; a cleaning element for each stripping element adapted to remove the leaf therefrom; a rotatably-mounted segment; and a pair of auxiliary surfaces between which the stripping element cooperates, the forward surface preventing the leaf from falling over the front of the stripping element and the rear surface preventing the leaf from moving beyond the range of the cleaning element.

35 11. A tobacco stemming machine comprising a pair of cooperating stripping elements for stripping the leaf from the stems; a cleaning element for each stripping element adapted to remove the leaf therefrom; a rotatably-mounted segment; and a pair of auxiliary surfaces between which the stripping element cooperates, the forward surface preventing the leaf from falling over the front of the

40 stripping element and the rear surface preventing the leaf from moving beyond the range of the cleaning element, the rear surface being composed of a brush.

45 12. A tobacco stemming machine comprising a pair of rotatably-mounted chains; co-

50 operating stripping elements mounted on the chains; a cleaning element for each cooperating stripping element adapted to remove the leaf therefrom; a pair of auxiliary surfaces rotatably mounted and cooperating with the stripping elements to prevent the leaf from moving beyond the range of the cleaning element; and a cover between the auxiliary surfaces to prevent any free leaves from falling over the edge of the auxiliary surfaces.

55 13. A tobacco stemming machine comprising a pair of rotatably-mounted chains; cooperating stripping elements mounted on the chains; a cleaning element for each cooperating stripping element adapted to remove the leaf therefrom; and a brush mounted on each chain and immediately in the rear of each stripping element movable against the stripped tobacco leaves to prevent the leaves from moving beyond the range of the cleaning element.

60 14. A tobacco stemming machine comprising a stripping element for stripping the leaf from the stem; a cleaning element for the stripping element adapted to strip the leaf therefrom; and a concave surface movably mounted and adapted to be moved in cooperation with the cleaning element after the passage of the stripping element to prevent the leaf from moving beyond the range of the cleaning element.

65 15. A tobacco stemming machine comprising a stripping element for stripping the leaf from the stem; a cleaning element for the stripping element adapted to strip the leaf therefrom; a concave surface movably mounted and adapted to be moved in cooperation with the cleaning element after the passage of the stripping element to prevent the leaf from moving beyond the range of the cleaning element; and a cam for actuating the concave surface toward and away from the cleaning element to permit the passage of the stripping element.

70 16. A tobacco stemming machine comprising a stripping element for stripping the leaf from the stem; a cleaning element for the stripping element adapted to strip the leaf therefrom; a concave surface movably mounted and adapted to be moved in cooperation with the cleaning element after the passage of the stripping element to prevent the leaf from moving beyond the range of the cleaning element; a rotatably-mounted cam in the form of an endless track; and means cooperating with the track and the surface to actuate the concave surface toward and away from the cleaning element to permit the passage of the stripping element.

75 17. A tobacco stemming machine comprising a stripping element for stripping the leaf from the stem; a cleaning element for the stripping element adapted to strip the leaf therefrom; a concave surface movably mounted and adapted to be moved in cooperation
